UNITED STATES PATENT OFFICE.

JAMES C. HYDE, OF WEST HAVEN, CONNECTICUT, ASSIGNOR TO THE WEST HAVEN BUCKLE COMPANY, OF SAME PLACE.

GARMENT-FASTENING.

SPECIFICATION forming part of Letters Patent No. 315,944, dated April 14, 1885.

Application filed February 24, 1885. (No model.)

To all whom it may concern:

Be it known that I, JAMES C. HYDE, of West Haven, in the county of New Haven and State of Connecticut, have invented a new 5 Improvement in Garment-Fastenings; and I do hereby declare the following, when taken in connection with accompanying drawings and the letters of reference marked thereon, to be a full, clear, and exact description of 10 the same, and which said drawings constitute part of this specification, and represent, in—

Figure 1, a perspective view showing the attachment as made to the end of a strap; Fig. 2, the attaching-plate as constructed 15 flat; Fig. 3, a perspective view of the same, showing the spurs and tongues turned up preparatory to attachment; Fig. 4, a transverse section through the tongues, flap, and strap after attachment; Fig. 5, a vertical section 20 through the flap, plate, strap, and one of the spurs after attachment; Fig. 6, a vertical central section of the attaching-plate, illustrating the method of applying the strap.

This invention relates to an improvement 25 in that class of garment-fastenings which are attached to the end of straps—such as stocking and sleeve supporters and various kinds of suspending devices—the invention relating particularly to the construction whereby the 30 fastening is secured to the strap.

Various tubular constructions have been made whereby the end of the strap would be embraced. Spurs have also been formed in the fastening, with tongues adapted to be turned down upon the strap after the strap has 35 been set upon the spurs, and the spurs themselves turned down, the tongues serving to cover the spurs.

The object of my invention is to construct 40 the fastening so that the end of the strap may be held firmly embraced by the clasp; and it consists in the construction as hereinafter described, and more particularly recited in the claims.

45 In illustrating my invention I show it as applied to a common well-known spring-clasp, in which A represents the one jaw to be fixed to the strap, and B the hinged jaw

hung to the fixed jaw A. The end of the fixed jaw is extended, and transversely through 50 this extension a slot, a, is made in length equal to the width of the strap to be attached. In cutting this slot, spurs b (more or less in number) are left upon one edge, preferably the lower edge. This slot leaves a projecting flap, d, above, below the slot, and on each side is a laterally-projecting tongue, e. 55 The spurs b are turned inward at right angles to the plane of the jaw, and the tongues e are also turned up in the same direction, as 60 seen in Fig. 3, preparatory to applying the strap. The strap C is passed through the slot a from the outside inward, and, as indicated in Fig. 6, its end brought down upon the fixed jaw A over the spurs b, as indicated 65 in broken lines, Fig. 6. Then the spurs are turned down, and then the flap d is turned over onto the spurs and upon the end portion of the strap, as seen in Fig. 5, the flap d closing the spurs and end of the strap between it and the jaw A. This done, the tongues e are turned inward over the flap d, as seen in Figs. 1 and 4, which secures the flap in its place hard upon the strap. The tongues e also cover the edge of the flap to prevent its 70 catching upon the garments. This construction of the attaching device makes it of the firmest possible character, and gives to the device, when attached, a neat and finished appearance.

80 While representing this attaching device as upon a common garment-clasp, it will be understood that it may be applied to any of the known clasps or equivalent garment-fastenings which are to be attached to the end of a strap, the construction of the attaching-plate being the same in any case.

While I prefer to apply the spurs b, they may be omitted entirely and a very firm attachment made by closing the flap d and the 90 tongues firmly upon the strap; but I prefer to employ the spurs.

I claim—

1. The herein-described improvement in attaching devices for garment-fastenings, consisting in the attaching-plate constructed with 95

a transverse slot, *a*, flap *d*, projecting above said slot, and with a transversely-projecting tongue, *e*, on each side of the plate and below the said slot, substantially as described.

5 2. The herein-described improvement in attaching devices for garment-fastenings, consisting in the attaching-plate constructed with a transverse slot, *a*, flap *d*, spurs *b b*, and

with a laterally-projecting tongue, *e*, on each side the plate below the slot, substantially as to described.

JAMES C. HYDE.
